1:1-ETHYLENE-2:2-DIPYRIDYLUM QUATERNARY SALTS

Ronald Frederick Homer, Wokingham, England, assignor to Imperial Chemical Industries Limited, London, England, a corporation of Great Britain
No Drawing. Filed May 2, 1962, Ser. No. 191,749
Claims priority, application Great Britain, Aug. 25, 1961, 30,742/61
9 Claims. (Cl. 71—2.5)

This is a continuation-in-part of application Serial No. 787,375, filed January 19, 1959, now abandoned.

This invention relates to new herbicides and more particularly it relates to dipyridylum quaternary salts which possess useful herbicidal properties.

The salts of the invention may be broadly described as 1:1'-ethylene-2:2'-dipyridylum quaternary salts having a lower alkyl radical located at one or more positions selected from the 4, 5 and 6 positions of the pyridylum ion and a lower alkyl radical located at one or more positions selected from the 4', 5' and 6' positions of the ion. These salts may be represented by the following formula:

wherein the R and R' substituents stand for lower alkyl, preferably alkyl containing from 1 to 4 carbon atoms, the R substituent being located at a position or positions selected from the group consisting of the 4, 5 and 6 positions and the R' substituent being located at a position or positions selected from the group consisting of the 4', 5' and 6' positions and X stands for an anionic radical. Typically, R and R' are methyl or ethyl and they are conveniently, but not necessarily the same.

Preferred compounds are the N:N'-ethylene-5:5'-dimethyl-2:2'-dipyridylum salts, for example, the dibromide or dichloride, and the corresponding 4:4' and 6:6' derivatives.

It is to be understood that the expansion anionic radical includes such radicals derived from inorganic and organic acids and any such radical may be used herein. The said anionic radicals may be interchanged one with another without destroying the herbicidal activity of the products of this invention. As suitable anionic radicals derived from inorganic acids there may be mentioned, for example, halide radicals such as chloride, bromide, and iodide radicals while the p-toluenesulphonate radical is representative of anionic radicals derived from organic acids. Other anionic radicals which may be mentioned are, for instance, sulphate, nitrate, bichromate and thiocyanate.

According to a further feature of the invention there is provided a process for the manufacture of the said dipyridyl derivatives which comprises interaction of the corresponding dipyridyl compound of the formula:

wherein R and R' have the meaning stated above and a quaternizing ethylene glycol di-ester.

As a suitable ethylene glycol di-ester there may be mentioned, for example, an ethylene dihalide, for example, ethylene dibromide and an ethylene disulphonate, for example, ethylene di-p-toluenesulphonate.

The reaction may be carried out, for example, by heating the reagents together or they may be heated together in the presence of an inert solvent or diluent, preferably a

2

high-boiling polar liquid, for example, nitrobenzene or β -ethoxyethanol.

The dipyridyl compounds used as starting material in the above process may be obtained according to the art, for example, by treatment of the appropriate 2-bromo-4- or 5-alkylpyridine with copper powder.

Although the preparative process described above is quite satisfactory for the preparation of compounds where X⁻ is, for instance, a chloride, bromine, iodine or p-toluenesulphonate ion, the process is not always satisfactory for the preparation of other compounds of this invention. Accordingly, as another aspect of the invention, the compounds of this invention can be prepared by a second process, in which a quaternary salt of the formula given above is treated with a suitable salt of an acid having the anion of the quaternary salt it is desired to make. Stated another way, there is provided a process for the manufacture of certain of the new dipyridyl derivatives which comprises interaction of a compound of the formula:

wherein R and R' have the meaning stated above and Y stands for an anionic radical, for example, a bromide radical or a p-toluenesulphonate radical and obtainable by the previously described process, with a salt of an acid derived from an anionic radical X, wherein X has the meaning stated above.

Thus, those compounds of the formula given above wherein Y stands for halogen, for example, bromine can be converted into certain of the new quaternary salts of the invention by treatment with a salt, for example, sodium iodide or silver chloride. The said interaction may be carried out in the presence of an inert solvent or diluent medium, for example, water.

As particularly useful quaternary salts, there may be mentioned, for example, those salts of the formula stated above wherein X stands for a bromide, chloride, iodide or p-toluenesulphonate radical.

The said new quaternary salts possess useful herbicidal properties. For example, these salts are useful as general herbicides against such representative plant species as wheat (*Triticum aestivum*), wild oats (*Avena fatua*), sugar beet (*Beta vulgaris*), mustard (*Sinapis alba*), kale (*Brassica oleracea*), cleavers (*Galium aparine*), and red clover (*Trifolium pratense*). Thus, according to a further feature of the invention, there are provided herbicidal compositions wherein the active herbicidal ingredient comprises one or more of the said new quaternary salts. Such compositions may be liquid compositions and may be, for example, aqueous solutions of the said new quaternary salts.

The said liquid compositions may advantageously contain auxiliary agents, for example, dispersing agents or wetting agents. The wetting or dispersing agent used can be a cationic or non-ionic surface-active compound, but in general anionic compounds should be avoided as these are likely to interact with the dipyridylum quaternary salt and lead to undesirable side effects. Suitable wetting agents may be, for example, condensation products of ethylene oxide with, for example, an alkyl phenol, for example, octylresol such that the said condensation products contain about one molecular proportion of octylresol condensed with about 8-10 molecular proportions of ethylene oxide.

The said liquid compositions may also contain additional ingredients, for example, agents which improve the adhering properties of the said liquid compositions to the

plant, for example, sodium carboxymethylcellulose and ammonium polymethacrylate.

The herbicidal compositions may also conveniently be in the form of solid compositions in which the new quaternary salts are admixed with inert pulverulent diluents, for example, talc, china clay, gypsum, basic slag, kieselguhr or bentonite and other colloidal clays. These powder compositions can also contain a wetting or dispersing agent if desired.

While the quaternary salts of the invention may be used for general herbicidal purposes as aforesaid, they are particularly useful as selective herbicides against grass species. This selective activity is unexpected and represents a very significant and advantageous distinction over the corresponding unsubstituted quaternary salts, i.e. the salts where R and R' stand for hydrogen (U.S. Patent 2,823,987).

The invention is illustrated but not limited by the following examples in which the parts are by weight:

EXAMPLE 1

A mixture of 4 parts of 5:5'-dimethyl-2:2'-dipyridyl, 10 parts of ethylene dibromide and 25 parts of nitrobenzene is heated at 170-180° C., for 8 hours and then cooled. The mixture is filtered and the solid residue is dissolved in 15 parts of hot water, treated with carbon and filtered. The filtrate is then diluted with 100 parts of acetone and the mixture is filtered. The solid residue so obtained is N:N'-ethylene-5:5'-dimethyl - 2:2' - dipyridylum dibromide, M.P. 330-335° C., with decomposition.

EXAMPLE 2

A mixture of 16 parts of 4:4'-dimethyl-2:2'-dipyridyl, 100 parts of nitrobenzene and 30 parts of ethylene dibromide is heated at 170-180° C., for 7 hours and then cooled. The mixture is filtered and the solid residue is dissolved in 100 parts of hot water, treated with carbon and filtered. The filtrate is evaporated to dryness and the residue is dissolved in 95% ethanol and the solution is diluted with ether. The mixture is filtered and the solid residue so obtained is N:N'-ethylene-4:4'-dimethyl-2:2'-dipyridylum dibromide, M.P. 268-270° C.

The N:N'-ethylene-4,5:4',5-tetramethyl-2:2'-dipyridylum dibromide or the corresponding 4,6:4',6-tetramethyl- or 4,5,6:4',5',6-hexamethyl-derivatives may be prepared in essentially the same manner starting with 4,5:4',5-tetramethyl-2:2'-dipyridyl, 4,6:4',6-tetramethyl-2:2'-dipyridyl and 4,5,6:4',5',6-hexamethyl-2:2'-dipyridyl, respectively.

EXAMPLE 3

A mixture of 6.5 parts of 4:4'-diethyl-2:2'-dipyridyl and 40 parts of ethylene dibromide is heated under reflux at 140° C. for 16 hours and cooled. The mixture is filtered and the solid residue is dissolved in 50 parts of ethanol, treated with carbon and filtered. The filtrate is evaporated to dryness and the residue is triturated with acetone and filtered. The solid residue so obtained is N:N'-ethylene-4:4'-diethyl-2:2'-dipyridylum dibromide, M.P. 310° C.

EXAMPLE 4

A mixture of 9.2 parts of 5:5'-dimethyl-2:2'-dipyridyl, 20 parts of ethylene di-p-toluenesulphonate and 60 parts of nitrobenzene is heated at 160-170° C., for 3 hours and then cooled. The reaction mixture is added to 300 parts of acetone and the mixture is filtered. The solid residue is dissolved in aqueous ethanol, treated with carbon and filtered. The filtrate is diluted with acetone and the mixture is filtered. The solid residue so obtained is N:N'-ethylene - 5:5', - dimethyl-2:2'-dipyridyl di-p-toluenesulphonate, M.P. 220° C.

EXAMPLE 5

A mixture of one part 6:6'-dimethyl-2:2'-dipyridyl and 10.9 parts of ethylene dibromide was heated in a sealed tube at 190-195° C., for 4 hours. The tube was then cooled, its contents dissolved in a small quantity of water

and the resulting aqueous solution boiled with charcoal and filtered. The filtrate obtained was evaporated to dryness leaving a residue which was then recrystallized from a mixture of methanol and acetone, and the quaternary salt N:N'-ethylene - 6:6'-dimethyl - 2:2' - dipyridylum dibromide was thus isolated as a white crystalline solid, melting point about 320° C., with darkening and shrinking.

EXAMPLE 6

A mixture of one part of 6:6'-dimethyl-2:2'-dipyridyl, 10.9 parts of ethylene dibromide and 18 parts of nitrobenzene was heated under reflux for 8 hours. The resulting mixture was cooled, mixed with 80 parts of ether, and the precipitate thus obtained was collected. This precipitate was then dissolved in water and N:N'-ethylene-6:6'-dimethyl-2:2'-dipyridylum dibromide was isolated from the resulting aqueous solution by the method used for treating the aqueous solution referred to in Example 5.

EXAMPLE 7

A solution of 1 part of N:N'-ethylene-5:5'-dimethyl-2:2'-dipyridylum dibromide in 800 parts of water containing 2.4 parts of a condensation product of octylcresol with 8-10 molecular proportions of ethylene oxide (as wetting agent) is sprayed at the rate of 20 gallons to the acre on to a mixed stand of seedling plants. After 14 days there is complete kill of wild oat (*Avena fatua*), sugar beet (*Beta vulgaris*), and red clover (*Trifolium repens*), and severe damage to wheat (*Triticum aestivum*), kale (*Brassica oleracea moellerii*) and mustard (*Sinapis alba*).

EXAMPLE 8

A solution of 5 parts of N:N'-ethylene-4:4'-dimethyl-2:2'-dipyridylum dibromide in 1000 parts of water containing 3 parts of a condensation product of octylcresol with 8-10 molecular proportions of ethylene oxide (as wetting agent) is sprayed at the rate of 100 gallons to the acre on to a mixed stand of seedling plants. After 14 days, there is complete kill of wild oat (*Avena fatua*), wheat (*Triticum aestivum*), sugar beet (*Beta vulgaris*), red clover (*Trifolium repens*), kale (*Brassica oleracea*) and mustard (*Brassica alba*).

EXAMPLE 9

An aqueous solution of N:N'-ethylene-6:6'-dimethyl-2:2'-dipyridylum dibromide was sprayed on the following representative plant species: wheat (*Triticum aestivum*), wild oats (*Avena fatua*), mustard (*Sinapis alba*), kale, (*Brassica oleracea*), sugar beet (*Beta vulgaris*), red clover (*Trifolium pratense*) and cleavers (*Galium aparine*). Four aqueous compositions were tested, containing respectively 0.2, 0.1, 0.05, 0.025 lb./gallon of the test chemical, each composition containing 0.1% by weight of a wetting agent consisting of a condensation product of one mole of p-octyl phenol with 7-8 moles of ethylene oxide. The four aqueous compositions were sprayed on the seven representative plant species in an amount of 20 gallons/acre. Thus, the amount of the dipyridylum salt applied to the plant species by using the four aqueous compositions corresponded to rates of 4, 2, 1 and 0.5 lb. of test chemical/acre.

The results obtained seven days after spraying are set out in the table below in which the herbicidal activity of each of the compositions tested is indicated by a grading number from 0 to 4.

These grading numbers have the following meanings:

- 0—Complete kill
- 1—Very severe damage with partial kill
- 2—Severe damage
- 3—Moderate damage
- 4—Slight damage

It will be seen that at the rate of 2 lb./acre a complete kill was obtained of all the plant species tested with the

exception of wheat which was, however, very severely damaged.

It will be seen from the above table that the dimethyl analogues have an unusually high ratio of activity against

Rate of application (lb./acre)	Wheat	Wild oats	Sugar beet	Mustard	Kale	Cleavers	Clover
4-----	0	0	0	0	0	0	0
2-----	1	0	0	0	0	0	0
1-----	1	0	1	0	0	3	0
0.5-----	1	0	0	1	0	4	1

EXAMPLE 10

This example illustrates the unique selectivity of the compounds of the present invention against grass species and for this purpose, a preferred dipyridylum salt of 2,823,987, N:N'-ethylene-2:2'-dipyridylum dibromide, was subjected to the following comparative tests with the dimethyl-substituted analogs of Examples 1, 2 and 5 herein.

The four compounds were each applied to a standard range of test plant species by spraying the plants with aqueous solutions of a concentration corresponding to $\frac{1}{6}$ lb. in 100 imperial gallons of water per acre, the solutions each containing 1% by weight of a non-ionic wetting agent containing a condensate of p-nonyl phenol and ethylene oxide.

The sprayed plants were examined during the following 9 days and the damage suffered by the plants on the ninth day was assessed as a percentage compared with healthy (100%) replicate plants which had not been sprayed. The results obtained are shown below in Tables 1 and 2 which relate respectively to broad-leaved species and grass species. The figures for broad leaved species were obtained as mean values for the species mustard, kale, sugar beet, cleavers and clover, and the figures for grasses as mean values obtained for wheat and wild oats.

Table 1

PERCENTAGE DAMAGE TO BROAD-LEAVED SPECIES AT 9 DAYS

Compound:	Percentage
N:N'-ethylene-2:2'-dipyridylum dibromide	60
4:4'-dimethyl analogue (Example 2)	16
5:5'-dimethyl analogue (Example 1)	16
6:6'-dimethyl analogue (Example 5)	36

Table 2

PERCENTAGE DAMAGE TO GRASS SPECIES AT 9 DAYS

Compound:	Percentage
N:N'-ethylene-2:2'-dipyridylum dibromide	50
4:4'-dimethyl analogue (Example 2)	30
5:5'-dimethyl analogue (Example 1)	60
6:6'-dimethyl analogue (Example 5)	60

From the data in the above tables, an index of selectivity, representing the ratio of percentage damage on grass species to damage on broad leaved species at 9 days, was calculated for each compound. A value of 1.0 for this represents no selectivity while index value above 1.0 shows a selective activity against the grass species. The index values for the four compounds tested at 9 days are shown below in Table 3.

Table 3

Compound:	Index of selectivity
N:N'-ethylene-2:2'-dipyridylum dibromide	0.83
4:4'-dimethyl analogue (Example 2)	1.89
5:5'-dimethyl analogue (Example 1)	3.70
6:6'-dimethyl analogue (Example 5)	1.67

the grass species. In fact, the ratio of the 5:5'-dimethyl derivative is almost 4 and, in each instance, the index for the dimethyl analogue is at least twice the index for the N:N'-ethylene-2:2'-dipyridylum dibromide. This is illustrative of the unexpected and unique characteristics of the products of the present invention. These products also function more slowly than the non-alkylated counterparts and are, therefore, more advantageous in those cases where a slower rate of activity is claimed. The unusual nature of the present products is further evident from the fact that the 3:3'-dialkyl isomers demonstrate little or no herbicidal activity when compared to the 4:4', 5:5' and 6:6'-derivatives described herein.

What is claimed is:

1. A 1:1'-ethylene-2:2'-dipyridylum quaternary salt having a lower alkyl radical substituent located at a position selected from the 4, 5 and 6 positions of the dipyridylum ion and a second lower alkyl radical located at a position selected from the 4', 5' and 6' positions of the said ion.
2. N:N'-ethylene-5:5'-dimethyl-2:2'-dipyridylum dichloride.
3. N:N'-ethylene-4:4'-dimethyl-2:2'-dipyridylum dichloride.
- 35 4. N:N'-ethylene-6:6'-dimethyl-2:2'-dipyridylum dichloride.
5. A herbicidal composition comprising, as the active herbicidal ingredient, a herbicidally effective amount of a 1:1'-ethylene-2:2'-dipyridylum quaternary salt having a lower alkyl radical substituent located at a position selected from the 4, 5 and 6 positions of the dipyridylum ion and a second lower alkyl radical located at a position selected from the 4', 5' and 6' positions of the said ion, 45 a herbicide carrier and a surface-active agent.

6. The method of selectively controlling grass species which comprises applying thereto a herbicidally effective amount of a 1:1'-ethylene-2:2'-dipyridylum quaternary salt having a lower alkyl radical substituent located at a position selected from the 4, 5 and 6 positions of the dipyridylum ion and a second lower alkyl radical located at a position selected from the 4', 5' and 6' positions of the said ion.

- 55 7. The quaternary salt of claim 1 wherein the alkyl radicals are methyl radicals in the 5 and 5' positions.
8. The quaternary salt of claim 1 wherein the alkyl radicals are methyl radicals in the 4 and 4' positions.
9. The quaternary salt of claim 1 wherein the alkyl radicals are methyl radicals in the 6 and 6' positions.
